Attorney.

UNITED STATES PATENT OFFICE.

WILLIAM B. ARNOLD, OF NORTH ABINGTON, MASSACHUSETTS; ABBIE L. ARNOLD AND J. BUTLER STUDLEY EXECUTORS OF SAID WILLIAM B. ARNOLD, DECEASED.

WELT FOR BOOTS AND SHOES.

1,357,676.

Specification of Letters Patent. Patented Nov. 2, 1920.

Application filed September 11, 1918. Serial No. 253,495.

To all whom it may concern:

Be it known that I, WILLIAM B. ARNOLD, a citizen of the United States, residing at North Abington, county of Plymouth, and
5 State of Massachusetts, have invented an Improvement in Welts for Boots and Shoes, of which the following description, in connection with the accompanying drawings, is a specification, like characters on the
10 drawings representing like parts.

The invention to be hereinafter described relates to welts for boots and shoes. These welts must be of strong, tough, high grade leather to successfully bear the heavy duty
15 of holding the stitching for connecting the welt to the inner sole and upper. The high cost of this grade of leather renders it important to employ as small amount of leather therein as practicable without sacrifice of necessary strength. A slight saving in welt material for a pair of boots or shoes multiplies into a big economy in the manufacture of large quantities.

One of the aims and purposes of the
25 present invention, therefore, is to provide a welt requiring less width in the production thereof, and having as much, if not greater strength, than welts heretofore used. In carrying the invention into practical effect,
30 the welt and stitch receiving channel may be so formed that the inner margin of the welt when bent to present its grain face for engagement with the upper, will cause the inner edge of the welt to lie in a plane substantially flush with the flesh face of the
35 welt, and thereby eliminate the necessity for trimming the welt, with a consequent saving in welt material. For example, a welt a yard long having a thickness of $\frac{1}{8}$ "
40 and a width of $\frac{1}{2}$ " usually costs eight cents. A welt of this size formed and provided with a stitch receiving channel embodying the invention may enable $\frac{1}{2}$ " reduction in the width of the welt, thereby saving about
45 one-half cent in the cost of a yard of the welt.

Another object of the invention is to provide a welt having a deep stitch receiving channel with its bottom in such a position that when the inner edge of the welt is bent for presentation to the upper, a substantial amount of leather will be between the bottom of the groove and the surface of the welt engaging the upper, thereby providing
55 strong anchorage for the stitching.

And another object of the invention is to provide a welt which may be easily and perfectly bent to conform to the contour of the boot or shoe.

With the aforesaid and other objects in view, the character of the invention may be best understood by reference to the following description of one good form thereof shown in the accompanying drawing, wherein:

Figure 1 is a transverse vertical section through a completed shoe having a welt embodying the invention;

Fig. 2 on an enlarged scale is a transverse vertical section through a portion of an upper, its lining, inner sole, and a welt embodying the invention, showing the parts as they appear prior to trimming the upper and its lining;

Fig. 3 is a view similar to Fig. 2 showing the parts as they appear after the trimming and beating-out operation;

Fig. 4 is a transverse section through a welt having beveled inner and outer edges before the stitch receiving channel is formed therein;

Fig. 5 is a transverse section of the welt showing one of the slits therein in the production of the channel;

Fig. 6 is a transverse section through the welt showing the form of the channel after both slits have been cut therein;

Fig. 7 is a perspective view of the completed channel;

Fig. 8 is a transverse section of the welt showing the form thereof after having its inner edge bent for presentation to the upper of the boot or shoe, and showing the position of the stitching in the channel.

The welt may be variously formed, but preferably it is produced from a blank by cuts inclined to the faces of the blank to produce parallel beveled inner and outer edges, such as are shown in Letters Patent, No. 1,122,845, granted to me December 29, 1914.

Referring to the drawing, one form of welt made in accordance with my invention may comprise a body 1 (Fig. 7) of substantially uniform thickness, and having a flesh face 3 and a grain face 5. The inner edge 7 and the outer edge 9 may be inclined with respect to the faces of the body of the welt, and in the present instance, are in substantial parallelism, the construction being

such that the welt will have an obtuse angle 11 between the outer edge and the grain face thereof, and an obtuse angle 13 between the inner edge and the flesh face of the welt, as 5 will be noted in Fig. 4.

An important feature of the invention, as stated, relates to the form and location of the stitch receiving channel. In the present instance of the invention, this channel

- 10 is cut a substantial depth into the flesh face of the welt with its inner wall 15 substantially parallel to the inner edge of the welt, and its outer wall 17 curved or inclined with respect to the inner wall, and meeting the
- 15 same to form a channel 27. The incisions producing these walls preferably cut the flesh face of the welt along lines a substantial distance apart to form a channel having an ample opening. The inner wall of
- 20 the channel is closely adjacent to the inner beveled edge of the welt, and leaves a thin lip 21 between them.

Any suitable instrumentality may be employed for cutting the channel described, 25 but preferably it is produced by first making an incision 23 close to and in substantial parallelism with the inner edge of the welt, as will be noted in Fig. 5, and then making a second incision oblique to and 30 meeting the incision 23, as will be noted in Fig. 6. These incisions may be straight, but preferably their inner ends should have a rounded form to conform to the contour of the stitching seated in the bottom of the 35 channel.

Having described the construction of the welt, its application to the boot or shoe will now be described, with more particular reference to Figs. 1, 2 and 3, wherein is 40 shown an inner sole 29 having a stitch receiving and retaining flange or shoulder 31 terminating in a lip 33 which forms a continuation of the feather edge 35 of the inner sole. The edge portions of the upper 36 45 and its lining 36^a are laid in the recess formed by said lip and feather edge, and are bent inward to conform to said recess.

The welt is then bent to present the portion 37 of its grain face against the outer 50 surface of the upper, and the inner sole, upper, its lining and the welt are securely connected by the through and through stitching 39 embracing the inner sole flange or shoulder 31 and the bottom of the channel.

55 When the inner edge of the welt is bent to present the portion 37 of its grain face for engagement with the upper, the inner beveled edge 7 of the welt is brought to a position where it is in a plane substantially 60 parallel and flush with the flesh face of the body of the welt, as will be noted in Fig. 2. When the welt is thus bent, the edge portions of the walls of the channel will close around the stitching and may meet or nearly 65 meet at the flesh face of the welt, and the

stitching will engage the bottom of the channel along a line substantially midway between the flesh and grain faces of the welt. The construction is such that a substantial body of leather will be between the bottom 70 of the groove and the grain face portion 37 of the welt engaging the upper, and thereby effectively withstand the pull of the stitching on the welt.

Since the inner beveled edge of the welt 75 is substantially flush with the flesh face thereof, it is not necessary to trim the inner portion of the welt, since the substantial portion of the welt which usually projects above the flesh face of the welt is absent. 80 As a consequence, the full amount of welt material between the stitch receiving channel and the upper is utilized in resisting the pull on the stitching. The formation of the channel as described enables the location 85 thereof nearer to the inner edge of the welt than has heretofore been possible, and therefore, a welt may be used of a less overall width than hitherto required. This saving, 90 although small in the welt for a single pair of boots or shoes, multiplies into a large economy in the production of large numbers of boots and shoes. It will be noted that this saving is not obtained with sacrifice in strength of the welt, but, on the contrary, 95 the welt has as much, if not more strength than welts heretofore used.

In some cases the portion of the lip 33 of the inner sole and the portions of the upper and its lining projecting beyond the flesh face 100 of the welt, may be trimmed substantially flush with said face, as will be noted in Fig. 3, or if desired, the trimming step may be eliminated, and said projecting portions may be bent over and flattened toward the 105 inner sole in beating out the welt in the usual manner.

Then the filler 41 (Fig. 1) may be laid on the inner sole within the boundary of the welt, and the latter may be secured to the 110 outer sole 43 by stitching 45, as will be noted in Fig. 1.

The welt may be formed with beveled inner and outer edges as described, or with a beveled inner edge and an outer edge normal to the faces of the welt. A greater saving in stock is effected if the welt is made with beveled inner and outer edges, since less stock need be removed in trimming the outer edges of the welt and outer sole. In 115 fact, the angle of the beveled outer edge may be such that the latter does not need to be trimmed off, but is suitably formed in the rounding operation.

Since the channel is formed to present an 120 ample opening, and extends a substantial depth into the body of the welt, the flexibility of the welt is desirably increased, thus permitting the welt to be readily flexed about and applied to the shoe, and it fits 125 130

more flexibly and easily to the shoe than a welt having a shallow channel located a substantial distance from the inner edge of the welt.

5 By my invention there is provided a welt which may be made of less material than heretofore required, thereby effecting an important saving in the high grade, expensive leather used for welts, but without loss of 10 the necessary strength of material between the stitching and the inner edge of the welt.

It will be understood that the invention is not limited to the specific embodiment shown, but that various deviations may be 15 made without departing from the spirit and scope of the appended claims.

What is claimed is:—

1. A welt having a substantially uniform thickness throughout the body portion of 20 the welt, an inner edge beveled with respect to the flesh and grain faces of the welt, a deep stitch-anchoring-channel having an inner wall substantially parallel to the inner beveled edge of the welt and an outer wall 25 inclined toward and to said inner wall, the

opening of said channel and the location of the bottom thereof being such that the portion of the welt between the inner wall of the channel and the inner beveled edge of the welt may wrap about the stitching and present 30 said inner beveled edge in a plane substantially flush with the flesh face of the welt.

2. A leather welt having grain and flesh faces and a substantially uniform thickness throughout the body portion of the welt, and 35 a stitch-anchoring-channel positioned sufficiently close to the inner edge of the welt to form a relatively thin lip having its end flush with a face of the welt, said channel having an ample depth and opening and located so closely adjacent to the inner edge 40 of the welt that on longitudinally bending of the inner edge portion of the welt for presentation to the upper of a shoe, the inner edge will be substantially flush with the 45 flesh face of the welt.

In testimony whereof I have signed my name to this specification.

WILLIAM B. ARNOLD.
